HOLE CUTTER FOR COIN COLLECTION
CARDS OR SIMILAR ARTICLE

Forrest I. Sollenberger, Arlington, Va.

Application July 8, 1949, Serial No. 3,785

Term of patent 14 years

(CL. D74—1)

To all whom it may concern:

Be it known that I, Forrest I. Sollenberger, a citizen of the United States, residing at Arlington, in the county of Arlington and State of Virginia, have invented a new, original, and ornamental Design for a Hole Cutter for Coin Collection Cards or Similar Article, of which the following is a specification, reference being had to the accompanying drawing, forming part thereof.

Fig. 1 is a top plan view of a hole cutter for coin collection cards or similar article, showing my new design;

Fig. 2 is a side elevational view;

Fig. 3 is a sectional view taken on line 3—3 of Fig. 2; and

Fig. 4 is an end elevational view thereof.

I claim:

The ornamental design for a hole cutter for coin collection cards or similar article, as shown.
FORREST I. SOLLENBERGER.
